COMBINED MINIATURE STAGE AND RECORD PLAYER

Eileen H. Belden, Lynbrook, N. Y.

Application August 1, 1950, Serial No. 11,519

Term of patent 14 years

(Cl. D56—4)

To all whom it may concern:

Be it known that I, Eileen H. Belden, a citizen of the United States of America, residing at Lynbrook, Long Island, in the county of Nassau and State of New York, have invented a new, original and ornamental Design for a Combined Miniature Stage and Record Player, of which the following is a specification, reference being had to the accompanying drawing, forming part thereof.

In the drawing:

Fig. 1 is a top plan view of a combined miniature stage and record player, showing my new design;

Fig. 2 is a front view;

Fig. 3 is a right side view. The left side view of the cabinet presents the same appearance as the right side view of Fig. 3.

The dominant features of my design reside in those portions shown in full lines in the drawing.

I claim:

The ornamental design for a combined miniature stage and record player, substantially as shown, and described.

EILEEN H. BELDEN.
